UNITED STATES PATENT OFFICE

118,447

DESIGN FOR A DART BOARD

Levant M. Heinze, Prospect Park, Pa.

Application September 13, 1939, Serial No. 87,178

Term of patent 14 years

To all whom it may concern:

Be it known that I, Levant M. Heinze, a citizen of the United States, residing at Prospect Park, in the county of Delaware and State of Pennsylvania, have invented a new, original, and ornamental Design for Dart Boards, of which the following is a specification, reference being had to the accompanying drawing, forming part thereof, in which the figure is a perspective view of a dart board showing my new design. The drawing is lined to indicate red and green coloring.

I claim:

The ornamental design for a dart board, as shown and described.

LEVANT M. HEINZE.
